Thomas H. Wood, Henry S. Hubbell & John E. Roberts, of Utica, N.Y.
Letters Patent No 892, Dated June 2, 1857.

The schedule referred to in these Letters Patent and making part of the same.

To all whom it may concern:

Be it known that we, Thomas H. Wood, Henry S. Hubbell, and John E. Roberts, of the City of Utica, and County of Oneida, and State of New York, have invented or produced a new and original design for a cooking stove, called the Polar Star, and we do hereby declare that the following is a full and exact description of the same, reference being had to the accompanying drawing, and the letters of reference marked thereon.

Figure 1, is a perspective view of the stove.

Letters A, A, the front plate. Letters B, B, the front doors.
Letters C, C, the side plate. Letters D, D, the side doors. Letters E, F, the feet.

What we claim as our invention or production, and desire to secure by Letters Patent, is the general design
